Virginia Broderick, Wauwatosa, Wis., assignor to Consoweld Corporation, Wisconsin Rapids, Wis., a corporation of Wisconsin

Filed Sept. 1, 1964, Ser. No. 81,544

Term of patent 14 years

(Cl. D87—3)

Fig. 1

Fig. 2

FIGURE 1 is a plan view of a plastic sheet material showing my new design wherein the design unit is successively set at right angles about an axis defined by each corner of each design unit as indicated by the extensions beyond the unit boundaries;

FIGURE 2 is a plan view of another embodiment of my design wherein the design unit is alternately inverted horizontally and matched vertically as indicated by the extensions beyond the unit boundaries;

FIGURE 3 is a plan view of a further embodiment of my design wherein the design unit is repeated in regular succession as indicated by the extensions beyond the unit boundaries; and

FIGURE 4 is an enlarged plan view of the design unit, which constitutes the essential feature of my new design.

I claim:

The ornamental design for a plastic sheet material or the like, substantially as shown and described.
